(57) **CLAIM**

The ornamental design for a golf bag having front pocket window for smart phone, as shown and described.

DESCRIPTION

FIG. 1 is a front elevational view of a smart phone pocket window on a golf bag positioned in an upright position; and FIG. 2 is a side elevational view of the golf bag positioned in an upright position; and, FIG. 3 is a rear elevational view of the golf bag positioned in an upright position. The broken lines in the drawing views are included to show unclaimed environment only and form no part of the claimed design.
